UNITED STATES PATENT OFFICE.

ROBERT McLAUGHLIN, OF BALTIMORE, MARYLAND.

REINFORCED CONCRETE.

954,128.

Specification of Letters Patent. Patented Apr. 5, 1910.

Application filed July 21, 1908. Serial No. 444,628.

To all whom it may concern:

Be it known that I, ROBERT McLAUGHLIN, a citizen of the United States, residing at Baltimore, in the State of Maryland, have 5 invented a certain new and useful Improvement in Reinforced Concrete, of which improvement the following is a specification.

My invention relates to an improved construction of reinforced concrete, and its object is to provide cheap, efficient and scientifically constructed reinforcing members which are to be incorporated in concrete beams, girders, or other supports whereby the least amount of metal will be employed 15 for a given strength as compared with the forms of construction now in general use.

A further object is to provide a construction which can be easily manufactured and set up without the use of much labor or time.

20 The leading and more important features of my invention consist in the application of the greater compressive strength of cast iron which is to resist the forces of compression in the concrete and thereby materially 25 reduce the sectional area of all the compressive members and consequently reduce their weight and cost.

In the accompanying sheets of drawing illustrating the features of my invention,— 30 Figure 1 is a longitudinal section of a reinforced concrete girder showing an articulated or jointed compression member, and a taper tension member. Fig. 2 is a transverse section of same on line 2—2 of Fig. 1. Fig. 3 is an enlarged sectional view of articulated or jointed compression member, showing bolt for holding pieces together and for putting initial compression into compression member. Fig. 4 is an end view of same with bolt 40 removed. Fig. 5 is a view in elevation of a tension member of varying sectional area, or tapering from a larger size at the middle to smaller sizes at both ends. Fig. 6 is a longitudinal section of reinforced concrete girder 45 having curved compression member composed of cast or wrought iron or steel pieces articulated or jointed by ball and socket joints and a bolt running through its axis to hold said pieces in position and for putting initial compression into member; and a tension member of wrought iron or steel either of uniform or of varying sectional area. Fig. 7 is a transverse section of same on line 50 11—11. Figs. 8 and 9 show modified forms 55 of the compression member.

Referring to Fig. 1 of the drawings, 1 represents the concrete of the girder or beam, having embedded therein the cast iron compression member 2, which, in this instance, is an articulated or jointed bar consisting of 60 a number of short sections or spools 2', put together with straight joints on a bolt 3, which passes through their axes to hold them together while being placed in position in the structure and also to give initial 65 compression. The spools are preferably made of conical form and placed in such relation to one another that a shoulder is formed at the joint, which shoulder forms a grip or bond for the concrete. 70

As is well known, cast iron can resist a compressive strain of 140,000 pounds to a square inch of cross sectional area, while that of the usual grade of steel or wrought iron is considerably less and never over 75 40,000 pounds; thus it will be readily seen from this that great advantages as to weight and cost of reinforcing material to be employed are obtained when cast iron is used to resist the compressive strains in reinforced 80 concrete, as pointed out in this specification.

The lower or tension member 4 is preferably composed of wrought iron or steel of varying sectional area and forms no part of 85 my present invention. This member assumes the form of a taper bar or bars having its or their largest dimension at the middle, and tapering to smaller dimensions at the two ends, which are preferably bent upwardly as shown, for the purpose of anchoring. The use of a bar tapering from the middle to smaller dimensions at both ends is based on the fact that the greatest bending 90 moment of a girder or beam occurs at its middle section; therefore the strength 95 should be greatest at that point.

In Figs. 6 and 7 the same general construction is shown as described in Figs. 1—6, except that a plurality of reinforcing members are employed, and instead of being straight the upper compression member is curved and the articulated spools or short sections 5 are provided with ball and socket joints, to enable them to assume any curvature on the positioning bar or rod 6, which is of the same construction and function as in Figs. 1—6. 6' are either uniform or varying in cross section, steel or wrought iron tension members. 100 105

From the foregoing description and illus- 110

trations in the drawings it will be seen that I have devised a cheap and efficient form of reinforced concrete construction, and while I have shown the compression and tension rods as of circular section they may be any other form in cross section, as for example, flat, square, hexagonal, or hollow.

Fig. 8 shows a compression member composed of plain cylindrical spool sections 12, 12, threaded on a retaining or positioning bar, while Fig. 9 shows the spools or articulated sections 13, provided with a circular flange 15, as indicated, for engaging the concrete when embedded therein.

Having now fully described my invention, what I claim as new and desire to secure by Letters Patent, is:—

1. A reinforced concrete structure having an element to resist compression strains consisting of an articulated bar comprising a series of connected and abutting cast iron spools or sections.

2. A reinforced concrete structure having an element to resist compression strains consisting of an articulated bar comprising a series of connected and abutting cast iron spools or sections having ball and socket joints.

3. A reinforced concrete structure having an element to resist compression strains consisting of an articulated bar comprising a series of connected and abutting cast iron spools or sections each of which is a frustum of a cone in shape and so arranged that the smaller end of one is in juxtaposition to the larger end of the next spool or section.

4. A reinforced concrete structure having an element to resist compression strains consisting of an articulated bar of cast iron having a hole through its axis and a retaining or positioning bar inserted in said hole.

5. A reinforced concrete structure having an element to resist compression consisting of an articulated bar of cast iron having a hole through its axis and a bolt inserted in said hole, said bolt being adapted to put initial compression in the bar.

In testimony whereof I affix my signature in presence of two witnesses.

ROBERT McLAUGHLIN.
